J. A. Miller Belfield, Atts

UNITED STATES PATENT OFFICE.

ALONZO ALDRICH, OF BELOIT, WISCONSIN.

PAPER-MAKING MACHINE.

Application filed October 18, 1922. Serial No. 595,257.

To all whom it may concern:

Be it known that I, ALONZO ALDRICH, a citizen of the United States, residing at Beloit, in the county of Rock and State of Wisconsin, have invented a certain new and useful Improvement in Paper-Making Machines, of which the following is a full, clear, concise, and exact description, reference being had to the accompanying drawings, forming a part of this specification.

My invention relates to paper making machines, and particularly to Fourdrinier machines.

One of the objects of the invention is to permit and arrange for the movement of the brest roll for convenience in applying a new wire to the machine.

Another object of the invention is to provide simple, practical and easily operated means for securing such brest roll movement.

In the accompanying drawings Fig. 1 is a side elevation of the brest roll end of a Fourdrinier machine having means embodying the invention for securing movement of the brest roll longitudinally of the table;

Fig. 2 is a side elevation of such table end with the brest roll adjusted;

Fig. 3 is a cross section taken on line 3—3 in Fig. 2.

Referring to the drawings, I show an end portion of a Fourdrinier machine comprising table side members 1—1, preferably in the form of channel bars, as best shown in Fig. 3. Table rolls 2—2 are mounted on the table by means of brackets 3—3 supported on and bolted to the upper member 1^a of the channel members 1—1. The brackets 3—3 extend beyond the ends of the side channel bars 1—1, as best shown in Fig. 2. The wire 5 is shown extended over the table rolls 2—2.

The brest roll 6 is shown mounted on a sliding frame or carriage conveniently composed of two sliding members 7—7 preferably in the form of channel bars fitting into the channel bars 1—1, said channel bars having saddle-like ends 8—8 supporting bearings 9—9 for the brest roll axle 10. Said saddles 8—8 are provided with projections or hook members 11 to engage cables 12 to support the end of the table, to permit the table to be elevated slightly and then moved out for applying a new wire in the form of a continuous or endless band.

The members 7—7 comprising the sliding brest roll frame are provided with rollers 13 and the channel members 1 are provided with rollers 14 for the lower flanges of said members 7. For sliding the adjustable brest roll frame I show a rotary hand wheel 15 having a handle 16 mounted in the bearing 17 (Fig. 3) secured to, or cast with the upper side of one of the channel bars 1, as shown in Fig. 3. The shaft 18 of wheel 15 has a pinion 19 meshing with a gear 20 on a cross shaft 21 which extends crosswise of the table from side to side thereof, as shown in Fig. 3. Said shaft 21 is provided with pinions 22—22 at or near its opposite ends and these pinions 22 mesh with racks 23 on the upper flanges of members 7—7. Thus rotation of the wheel 15 will cause movement of the brest roll frame in one direction or the other, and thereby move the brest roll 6 toward and away from the main body portion of the table.

For holding the members 7—7 in position in the table sides 1—1 I show bolts 24—25, and also show the members 7—7 provided with elongated slots 26 in which said bolts are located. The slots 26 are large enough to accommodate the cross shaft 21 so that the members 7—7 may slide relatively to said shaft. End portions 27 of the slots 26 are reduced in size, however, so as to accommodate only bolts 24, the reduction of the size of slots 26 limiting the extent of inward movement on the part of the sliding frame, (Fig. 2), the outward movement of the same being limited by the ends of slots 26, as shown in Fig. 1.

In Fig. 1 the machine is shown in operating condition with the table rolls 2 in position and the brest roll 6 in its outermost position by reason of the outward projection of its adjustable frame. In Fig. 2 the brest roll is shown adjusted inwardly as far as possible by its adjustable carriage, to permit which three of the table rolls 2 have been removed from their bearings, this being necessary to permit the inward movement of the brest roll 6. Such removed table rolls may, for convenience, be placed on top of other table rolls, as shown in dotted lines in Fig. 2, and the wire 5 lifted up and then the table end passed through it. In this adjusted position the application of the wire 5

to the whole Fourdrinier end is greatly facilitated.

It will be understood that changes and modifications may be made without departing from the spirit of the invention.

What I claim is:

1. A machine of the class specified having its table made detachable to permit application of a wire in endless form and also 10 having slideable supporting means for the brest roll, said supporting means being slideable in a direction and to an extent to place the brest roll in position for service with a wire on the table and also to place said roll 15 in position to permit the application of a new wire in endless form to the table and around said roll and mechanism for positively sliding said supporting means from one of said positions to another and back 20 again.
2. A machine of the class specified having its table made detachable to permit application of a wire in endless form and also 25 having a moving support carried by said table and in turn carrying the brest roll, said support being movably mounted to permit it to place the brest roll in position to hold the wire on the table for service and also to move the brest roll into position to 30 permit the application of the wire in endless form to the table and around said roll, and mechanism on the table for moving said support from one to the other of said positions and back again.
3. A machine of the class specified having 35 its table made detachable to permit application of a wire in endless form, a movable support carried by said table and in turn carrying the brest roll, said support being mounted to permit placing the brest roll in 40 position to carry a wire in service position on the table and also to permit moving the brest roll from said position to a position to 45 permit applying a new wire in endless form to said table and around said brest roll, and reciprocating power means carried by the table and arranged for positively reciprocating said support from one to the other of said positions and back again.
4. A machine of the class specified having 50 a laterally removable table for permitting application of a new wire in endless form, a movable support carried by the table and in turn carrying the brest roll, said support being mounted for sliding movement longitudinally of said table so as to position the brest roll for carrying a wire in service on the table and also to move it to position to 55 allow a new wire in endless form to be applied to the table and around said roll, and power mechanism mounted on the table for sliding said support from one to the other of said positions and back again.

5. In a Fourdrinier machine, the combination with the table of an adjustable brest

roll carriage mounted for sliding movement toward and away from the end of the table, said carriage comprising sliding members mounted to slide lengthwise of and relatively to the sides of the table, and means for adjusting said carriage comprising gearing meshing with racks on the table and a hand wheel for operating said gearing.

6. In a Fourdrinier machine, the combination with the table comprising channel members of a sliding brest roll carriage comprising channel members fitting in the table channel members, racks on said sliding channel members, a cross shaft extending between the table sides and provided with pinions meshing in said racks, a rotary hand wheel mounted on one of the table channel members, gearing between said hand wheel and said cross shaft, and bolts holding said carriage channel members in position, said carriage channel members being provided with longitudinal bolts to accommodate said cross shaft and with reduced extension for accommodating said bolts.

7. In a machine of the class specified, the combination with the table and brest roll therefor, of movable carriages carrying the brest roll and mounted on opposite sides of the table for movement longitudinally thereof and mechanism on the table for effecting such longitudinal movement of said carriages in unison.

8. In a machine of the class specified, the combination with the table and brest roll therefor, of sliding carriages carrying the brest roll and mounted on opposite sides of the table for sliding movement relatively thereto, and mechanism for sliding said carriages in unison, said mechanism including means extending between the opposite sides of the table and connected with said carriages.

9. A machine of the class specified having a laterally removable table provided with a horizontally slideable support carrying the brest roll.

10. A machine of the class specified having a laterally removable table provided with a horizontally slideable support carrying the brest roll and mechanism for sliding said support back and forth horizontally.

11. A machine of the class specified having a laterally removable table provided with a horizontally slideable support carrying the brest roll and mechanism mounted on said table and adapted to slide said support back and forth horizontally.

12. A machine of the class specified having a laterally removable table provided with a longitudinally slideable support carrying the brest roll, said support being mounted to maintain the top of the brest roll in alinement with the tops of the table rolls, when said support is moved.

13. A machine of the class specified having a laterally removable table provided with side table members which support the table rolls and move laterally with the table and also provided with a slidable support which carries the breast roll and is mounted upon said side table members and arranged to slide relatively thereto and longitudinally thereof.
- In witness whereof, I hereunto subscribe my name this 4th day of October, A. D. 1922.

ALONZO ALDRICH.
